UNITED STATES PATENT OFFICE.

ALADAR HOLLANDER, OF BERKELEY, CALIFORNIA, ASSIGNOR TO BYRON JACKSON
PUMP MFG. CO., OF BERKELEY, CALIFORNIA, A CORPORATION OF CALIFORNIA.

VARIABLE-HEAD IMPELLER MECHANISM.

Application filed October 19, 1927. Serial No. 227,310.

My invention is particularly applicable to centrifugal pumps although it may be used also for turbine water wheels wherein the pressure or head under which the impeller 5 operates varies over a wide range.

The invention is also applicable to the exceptional case where radically different speeds of impeller operation are to be employed with the same head against or under 10 which the impeller operates.

It is to be understood that the impeller diameter, its vane angles and other characteristics are functions of the head against which the impeller operates and the speed of 15 rotation, and that a variation in either speed or head or both, involves a change in the impeller diameter and/or characteristics.

It is the object of my invention to provide 20 an impeller of varying diameter and characteristics to meet changes in head from time to time or in exceptional cases changes in speed or speed and head.

My invention is particularly applicable to 25 submerged pumps of large capacity and in the drawing and description below I have chosen a six thousand horsepower, three thousand gallon per minute pump adapted to operate under a delivery head having a seasonal variation of from 25 to 75 feet, that 30 is a range of three hundred per cent, while attaining efficiency and superior operating characteristics throughout, and combined with simplicity of construction.

By referring to the drawing my invention 35 will be made clear.

Fig. 1 represents a vertical cross section 40 through a submerged motor driven double centrifugal pump employing my invention with the parts assembled for operating under the lower head.

Fig. 2 is a fragmentary cross section of 45 the impeller and its associated elements with the parts assembled for the higher head.

Throughout the figures similar numerals 50 refer to identical parts.

The operating motor is indicated by the 55 numeral 1 adapted to drive the shaft 2 on which is mounted the impeller 3.

A volute casing into which the pumped 60 water is discharged is indicated at 4.

The impeller 3 is of the double type taking 65 suction water through a lower passage as indicated by the arrow 5, and through the upper passage as indicated by the arrow 6 and imparting thereto the necessary kinetic

energy to force the same through the volute 4 and against the delivery head.

Where low heads are involved such as 25 to 40 feet the impeller 3 having the diameter indicated by the dimension line 7 is rotated 60 at the definite speed of the motor 1, and at such time the annular members 8 and 9 are bolted to and form a part of the volute casing, their inner faces 10 and 11 serving as a portion of the volute delivery passage, 65 whereas when the higher heads are to be pumped the members 8 and 9 are disconnected from the casing and moved inward and are bolted to the impeller 3 when they become a part of and a continuation of the 70 impeller, increasing its diameter to that shown by the dimension line 12.

The diameter of the runner or impeller 12 introduces the necessary characteristics to 75 enable the pump to operate at the same speed of the motor 1, while delivering the higher head, that is from 40 to 75 feet.

If the operation is under the high head 40 to 75 feet the parts are connected together as shown in Fig. 2, whereas under the lower 80 heads 25 to 40 feet the impeller 3 is stripped of the members 8 and 9 which are now fixed in the volute casing into the position of Fig. 1.

The changes of head here contemplated 85 are seasonal changes making necessary the changing of the effective impeller diameter and characteristics only at long intervals.

As a varied application of my invention it 90 will now be seen that the impeller having the diameter of 7 may be employed to pump a fixed head at one speed and the impeller having diameter and characteristics 12 may be employed to pump the same head at a reduced speed.

The gist of my invention is the modification of the impeller diameter and characteristics to suit changed conditions of head or speed or head and speed.

It will also be obvious that if instead of 100 employing the apparatus herein disclosed as a centrifugal pump to raise water when driven by a motor, it be employed as a turbine water wheel to generate power from falling water, and that in place of the motor 105 1 an electric generator be employed; the apparatus will function to drive the generator at a fixed speed under different heads corresponding with those to which the runner diameter and characteristics 7 and the 110

runner diameter and characteristics 12 are adapted: or at relatively different speeds under the same head.

I claim:

5. 1. In combination with an impeller and a volute casing, said casing chambered to receive and hold an impeller ring, an impeller ring of annular form adapted to be fixed about the periphery of said impeller and when so fixed to provide a continuation of said impeller blades and passages and when unfixed to be displaced clear of said impeller and to be held in said casing chamber and positioned with one of its side faces 10 to direct the discharge from said impeller.
2. In a centrifugal pump a double suction and double discharge impeller mounted on a shaft and within a casing a chamber on each side of said casing and between said impeller periphery and said casing, a pair of symmetrical ring members each adapted to normally repose in one of said chambers with their opposed surfaces forming a discharge passage between the said impeller and the 20 said casing, connecting means on each of said members constructed and adapted to secure said members adjacent each other and to said impeller and then forming a continuation of said impeller and thus an impeller of greater diameter and new characteristics.
3. In a centrifugal pump, an impeller, a casing having receiving space for ring means, ring means constructed and adapted

when secured to said impeller to increase the diameter of said impeller and when unfixed to be shifted into said space and remain stationary.

4. In a centrifugal pump, an impeller, a casing having receiving space for ring means, ring means constructed and adapted 40 when secured to said impeller to increase the diameter of said impeller and when unfixed to be shifted into said space and remain stationary, means fixing said ring means in said space.

45 5. In a centrifugal pump, an impeller, a casing having receiving space for ring means, ring means constructed and adapted when secured to said impeller to increase the diameter of said impeller and when unfixed to be shifted into said space and remain stationary, the face of said ring means forming a surface over which the impeller is adapted to discharge.

50 6. In a centrifugal pump, an impeller, a casing having receiving space for ring means, ring means constructed and adapted when secured to said impeller to increase the diameter of said impeller and when unfixed to be shifted into said space and remain stationary, the face of said ring means forming a surface over which the impeller is adapted to discharge, means fixing said ring means in said space.

55 ALADAR HOLLANDER.
